UNITED STATES PATENT OFFICE.

AXEL H. HELANDER AND CARL O. LINDROTH, OF PHILADELPHIA, PENNSYLVANIA, ASSIGNORS TO THE SOUTHWARK FOUNDRY AND MACHINE COMPANY, OF SAME PLACE.

COMPRESSOR OR BLOWING-ENGINE.

SPECIFICATION forming part of Letters Patent No. 616,667, dated December 27, 1898.

Application filed August 21, 1896. Serial No. 603,443. (No model.)

To all whom it may concern:

Be it known that we, AXEL H. HELANDER and CARL O. LINDROTH, citizens of the United States, residing in the city and county of Philadelphia, in the State of Pennsylvania, have invented certain new and useful Improvements in Compressors or Blowing-Engines, of which the following is a true and exact description, reference being had to the accompanying drawings, which form a part thereof.

Our invention relates to the construction and operation of the delivery-valves of air-compressors, particularly of those compressors known as "blowing-engines."

Heretofore various plans have been devised and used for utilizing the pressure of the air compressed in the cylinder of the blowing-engines to actuate the delivery-valve of the engine, and while many such devices have proved practicable and of great value in use they are as a rule open to the objection that depending, as they do generally, upon the existence of pressure in the receivers of the blowing-engine they do not work or work properly when there is no pressure in the receiver, as is generally the case when the engine is being started.

The object of our invention is to provide means for actuating the delivery-valves by the action of the air compressed in the main cylinder, which will come at once into properly operative condition on the starting of the engine; and the main feature of our new construction consists in the provision of a storage reservoir for compressed air from which the actuating-cylinders of the delivery-valves can draw the power necessary to put them into operation. This storage-reservoir may be one which will receive a supply of compressed air when the engine is in full operation and store it ready for use after the engine has ceased to work or one which is adapted to receive a charge of compressed air from a source extraneous to the engine itself; but preferably and whether fit to be used as above noted or not the storage-reservoir is connected both with the top and bottom of the main cylinder of the blowing-engines by passages fitted with

non-return valves and so that the first movements of the air-compressing piston will result in forcing air under pressure into the reservoir, from which it is drawn at proper times to actuate the delivery-valves of the engine.

The nature of our improvements, both general and specific, will be best understood as described in connection with the drawings, in which they are illustrated, and in which—

Figure 1 is a vertical section through the main cylinder of a blowing-engine, the section passing through the delivery-valves and through the actuating-cylinders by which such valves are operated, being taken, for instance, on the line 1 1 of Fig. 2. Fig. 2 is a plan view of the main cylinder with the head and receiver removed, showing the upper valve-actuating cylinder in section. Fig. 3 is a cross-sectional view on the line 2 2 of Fig. 2. Fig. 4 is an end view of one of the valve-actuating cylinders and connected parts. Fig. 5 is a central longitudinal vertical section through the lower valve-actuating cylinder and some of its connected parts, and Fig. 6 is a diagram illustrating the action of the valves which control the movement of the pistons in the valve-actuating cylinder.

A is the main or compressing cylinder of the engine, A' A' indicating the heads of the cylinder, in which, as shown, are formed the delivery-ports by which the air issues from the cylinder.

B B indicate the receivers for the compressed air; C C, the delivery-valves, the valve-rods of which are indicated at C' C', D D indicating the valve-actuating cylinders, each provided with a piston E, connected with the respective valve-stems C' C'.

F F are passages or pipes leading from the ends of the cylinder A to an air-storage receptacle F', a non-return valve f being situated in each pipe F. From the reservoir F' lead pipes F² F², each connecting through a port F³ with that side of the cylinder D the admission of air to which will cause the delivery-valve C to close.

H H indicate exhaust-pipes connecting with the ports F³ and preferably each provided

with a cock or regulable valve, as indicated at *h*, by which the resistance to the exhaust can be regulated.

- 5 G G indicate valves controlling at the same time the connection of the ports F³ with pipes F² and with the exhaust-pipes H. The spin-
dles of these valves G have connected with them levers G', the said levers being connect-
ed, as shown, by a rod G³, so that the valves
10 are enabled to move upward in opposite di-
rections, G² indicating a valve-actuating rod
leading to a cam crank or eccentric actuated
by a constantly-moving part of the engine
and by which the valves G G are operated.
15 From the opposite sides of the cylinders D
lead pipes I I, which open into the compressing-
cylinder A, as indicated at I' I'. The po-
sition of these openings should be as shown,
that they will each be open for about two-
20 thirds of the stroke of the piston as it moves
toward the end of the cylinder with which
they are connected, then closed by the piston
moving across them, and then opened again
shortly before the main piston (which is in-
25 dicated at *a*, Fig. 1) reaches the end of its
stroke. Thus in Fig. 1 the piston *a* is shown
as just clearing the lower opening I' as it
moves downward. The pipes I I are prefer-
ably provided with non - return or check
30 valves, as indicated at *i*, and in this case they
are also provided with a by-pass I², leading
around the check-valves *i* and preferably pro-
vided with a regulable stop-cock, as indicated
at *i*².
35 J indicates a supplemental storage-reser-
voir connected with the reservoir F' as by a
pipe J', which should have a cock, as *j*', and
connected also, as shown, with the reservoir
B of the engine by means of a pipe K, pro-
40 vided with a stop-cock *k*.
The operation of the engine is readily fol-
lowed. Assuming that both valves C are
closed and the piston A at the upper end of
the cylinder, the arrangement of the mechan-
45 ism actuating the valves G G will be such as
to open the passage leading from the upper
pipe F² through the port F³ into the upper
cylinder D, and on reaching the point marked
1 in the diagram Fig. 6 the passage from F²
50 to the upper cylinder D still remains open,
but the passage from the lower pipe F² to the
lower cylinder D is closed, and the passage
from said lower cylinder to the exhaust-pipe
H is open. Then as the piston A continues
55 to move downward air is at first forced from
the cylinder A through both pipes I I to the
front ends of the cylinders D and through the
lower pipe F into the reservoir F', from which
the air passes to the rear side of the upper
60 cylinder D, but does not enter the lower cyl-
inder D. Obviously as long as the upper cyl-
inder D is receiving air through its pipe I on
one side of the piston the pressure of this air
is being exactly balanced by the compressed
65 air admitted to the other side of the piston
through the reservoir F', and after the piston

a has passed the upper opening I' the air on
the front side of the piston is permitted to es-
cape back into the cylinder A through by-
pass I² and upperpipe I. Secondly, the upper 7
delivery-valve under the conditions named
will not be opened, but will be held firm in a
closed position. On the other hand, the air
entering the lower opening I' in the cylinder
A will act on the front face of the piston E 75
in the lower cylinder D, and as the port F³ in
the rear of the said cylinder is open to the at-
mosphere the piston E will move backward
and will open the lower delivery-valve C as
soon as the accumulated pressure becomes 80
sufficient to overcome the inertia and fric-
tional resistance of said valves. When the
piston *a* in passing downward reaches the
point 2, (diagrammatically illustrated in Fig.
6,) the valve-actuating mechanism will move 85
the lower valve G so as to throw the rear of the
lower cylinder into communication through
pipe F² with the storage-reservoir F', and the
lower opening being then cleared by the piston
a, as indicated in Fig. 1, the air is free to 90
escape from the front of the lower cylinder
D through by-pass I² of pipe I, whereupon the
pressure on the rear of piston E will move it
and close the valve, and the reason for sup-
plying the pipes I with non-return valves and 95
with the by-passes I² is to afford resistance to
the escape of air through the pipe I, a resist-
ance which can be easily regulated by means
of the cocks *i*² and which serves the purpose
of a dash-pot to prevent too sudden a move- 100
ment of the valve, and we may here properly
mention that the function of the cocks *h* in
the exhaust-pipes H H is precisely the same—
viz., to enable the resistance to the escape of
air from the rear of cylinder D to be nicely 105
regulated and preventing too sudden move-
ments of the valves in the other direction.
The adjustment of the valves should be such
that the lower delivery-valve C will close just
as the piston *a* comes to the bottom of its 110
stroke. Then as it moves upward the opera-
tions described are again repeated, except
that the positions of the upper and lower
valves G are reversed. As the pressure in
the reservoirs B B increases the pressure in 115
the reservoir F' also increases and in the same
proportion, and this is true also, though to a
less degree, of the pressure in the pipes I I.
The parallelism of pressure in the reservoir
F' and the reservoirs B B is important, be- 120
cause the resistance which the delivery-valves
oppose when being closed depends largely
upon the pressure in the receiver, but as the
power applied to the valve-operating cyl-
inders from the reservoir F' increases in pro- 125
portion to this resistance the valves will by
our device be closed substantially at the same
time under all conditions of use.

As described above, it will be seen that even
from the first stroke of the piston *a* we secure 130
power to close the delivery-valves. Obvi-
ously also in case of the stoppage of the en-

gine a certain amount of air under pressure will remain in the reservoir F' in condition for use as soon as the engine is restarted, and it is from certain points of view desirable that the reservoir F' should be supplemented by a reservoir such as J, in which a considerable volume of compressed air can be stored and kept for some time. Such a supplemental reservoir can be filled from the receiver of the engine, as shown, or, if convenient, may be filled from some other source of compressed air.

Having now described our invention, what we claim as new, and desire to secure by Letters Patent, is—

1. In a blowing-engine or compressor having discharge-valves as C C the combination with said valves of cylinders D D having pistons connected with the valves, passages as I I leading from the compression-cylinder of the engine to the cylinder by which compressed air is admitted to open the valves, a storage-reservoir for compressed air separate from and independent of the main compressed-air receiver of the engine but connected with and receiving its air from the engine, passages leading from said reservoir to cylinders D D, non-return valves situated in said passages, exhaust-ports leading from said cylinders, valves as G G adapted to connect cylinders D D with the reservoir and with the exhaust-ports and positively-actuated mechanism for moving said valves, all substantially as and for the purpose specified.

2. In a blowing-engine or compressor having discharge-valves as C C, the combination with said valves of cylinders D D having pistons connected with the valves, passages as I I leading from the compression-cylinder of the engine at distances from its ends greater than the breadth of the compressor-piston to the cylinders by which compressed air is admitted to open the valves, non-return valves as i situated in passages I I, a restricted passage or by-pass connecting the pipe-sections around said valve a storage-reservoir for compressed air separate from and independent of the main compressed-air receiver of the engine but connected with and receiving its air from the engine, passages leading from said reservoir to cylinders D D, exhaust-ports leading from said cylinders, valves as G G adapted to connect cylinders D D alternately with the reservoir and with the exhaust-ports and positively-actuated mechanism for moving said valves all substantially as and for the purpose specified.

3. In a blowing-engine or compressor having discharge-valves as C C, the combination with said valves of cylinders D D having pistons connected with the valves, passages as I I leading from the compression-cylinder of the engine at distances from its ends greater than the breadth of the compressing-piston to the cylinders by which compressed air is admitted to open the valves, a storage-reser-

voir for compressed air, separate from and independent of the main receiver of the engine passages as F F leading from the compressing-cylinder to said reservoir and having non-return valves as f f, passages as F' F' leading from the reservoir to the cylinders D D, exhaust-passages as H H leading from said cylinders and valves as G G actuated by the engine and adapted to control the communication of the cylinders D D with passages F' and H.

4. In a blowing-engine or compressor having discharge-valves as C C, the combination with said valves of cylinders D D having pistons connected with the valves, passages as I I leading from the compression-cylinder of the engine at distances from its ends greater than the breadth of the compressing-piston to the cylinders by which compressed air is admitted to open the valves, non-return valves as i situated in passages I I, a restricted passage or by-pass connecting the pipe-sections around said valve, a storage-reservoir for compressed air separate from and independent of the main receiver of the engine, passages as F F leading from the compressing-cylinder to said reservoir and having non-return valves as f f, passages as F' F' leading from the reservoir to the cylinders D D, exhaust-passages as H H leading from said cylinders and valves as G G actuated by the engine and adapted to control the communication of the cylinders D D with passages F' and H.

5. In a blowing-engine or compressor having discharge-valves as C C the combination with said valves of cylinders D D having pistons connected with the valves, passages as I I leading from the compressing-cylinder at distances from the ends greater than the breadth of the compressing-piston and by which passages air is admitted to cylinders D to open the valves, non-return valves as i situated in passages I, a restricted passage or by-pass connecting the pipe-sections around said valve-passages as F F' F F' leading from the ends of the compressing-cylinders to the closing side of the cylinders D said passages having non-return valves as f, and provision for the storage of compressed air on the delivery side of said valves and valves as G G actuated by the engine and arranged to control the opening of cylinders D to passages F F' and to an exhaust.

6. In a blowing-engine or compressor having discharge-valves as C C the combination with said valves of cylinders D D having pistons connected with the valves, passages as I I leading from the compressing-cylinder at distances from its ends greater than the breadth of the compressing-piston and by which passages air is admitted to the cylinder D to open the valve, non-return valves as i situated in passages I, a restricted passage or by-pass connecting the pipe-sections around said valve-passages as F F' F F' leading from

the ends of the compressing-cylinders to the closing side of the cylinders D, said passages having non-return valves as f, and provision for the storage of compressed air on the delivery side of said valves, a connection F' between said passages and valves as G G actuated by the engine and arranged to control

the opening of cylinders D to passages F F² and to an exhaust.
